U.S. Appl. No. 15/046,517, Wunderlin.

Primary Examiner — Darlington Ly

(74) Attorney, Agent, or Firm — Mitchell Law PLLC;
Matthew W. Mitchell(57) **CLAIM**

The ornamental design for a balance bike, as shown and described.

DESCRIPTION

FIG. 1 is a top, front, and left-side perspective view of the balance bike showing my new design;
FIG. 2 is a bottom, front, and right-side perspective view thereof;

FIG. 3 is a left-side elevation view thereof;

FIG. 4 is a right-side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the drawings illustrate portions of the balance bike that forms no part of the claimed design.
